UNITED STATES PATENT OFFICE

150,917

DESIGN FOR A WATER BOWL FOR STOCK

Vernon R. Berg, Marshfield, Wis.

Application March 30, 1946, Serial No. 128,119

Term of patent 14 years

(Cl. D12—2)

To all whom it may concern:

Be it known that I, Vernon R. Berg, a citizen of the United States, residing at Marshfield, in the county of Wood and State of Wisconsin, have invented a new, original, and ornamental Design for a Water Bowl for Stock, of which the following is a specification, reference being had to the accompanying drawing, forming part thereof.

Fig. 1 is a plan view of a water bowl for stock, showing my new design.

Fig. 2 is a side elevation of the bowl shown in Fig. 1.

Fig. 3 is a view taken in cross-section on the line 3—3 of Fig. 1.

I claim:

The ornamental design for a water bowl for stock, as shown.

VERNON R. BERG.
